(57) **CLAIM**

The ornamental design for a gear shift coat hanger, as shown and described.

DESCRIPTION

FIG. 1 is a perspective view of a gear shift coat hanger in accordance with one embodiment of the present invention; FIG. 2 is a top view of the gear shift coat hanger of FIG. 1; FIG. 3 is a left side view of the gear shift coat hanger of FIG. 1;

FIG. 4 is a front view of the gear shift coat hanger of FIG. 1;

FIG. 5 is a right side view of the gear shift coat hanger of FIG. 1;

FIG. 6 is a bottom view of the gear shift coat hanger of FIG. 1; and,

FIG. 7 is a back view of the gear shift coat hanger of FIG. 1.

It will be understood that the dashed lines presented in the drawings are for illustration only, and do not form a part of the claimed design.
